UNITED STATES PATENT OFFICE.

CHARLES M. THOMPSON, OF NEW PHILADELPHIA, OHIO.

CHANNELING-TOOL.

1,166,277.

Specification of Letters Patent. Patented Dec. 28, 1915.

Application filed December 10, 1914. Serial No. 876,543.

To all whom it may concern:

Be it known that I, CHARLES M. THOMPSON, a citizen of the United States, residing at New Philadelphia, in the county of Tuscarawas and State of Ohio, have invented 5 certain new and useful Improvements in Channeling-Tools; and I do declare the following to be a full, clear, and exact description of the invention, such as will enable others skilled in the art to which it appertains to make and use the same.

This invention relates to hand tools of the type used for grooving and channeling leather, more particularly the soles of boots 10 and shoes.

15 The object of the invention is to provide a simply constructed, durable and efficient device of this character for cutting a thin channel around the edges of the lower sides 20 of shoe soles, the parts of which are adjustable to regulate the depth of the cut and the distance from the edge within a horizontal limit.

With these and other objects in view, the 25 invention consists of certain novel features of construction, and the combination and arrangement of parts as will be hereinafter more fully described and claimed.

In the accompanying drawings: Figure 1 30 represents a perspective view of this improved channeling tool; Fig. 2 is a side elevation thereof showing it applied; Fig. 3 is a transverse vertical section taken on the line 3—3 of Fig. 2; Fig. 4 is a bottom plan 35 view thereof.

In the embodiment illustrated a head 1 is shown having a shank 2 extending at an oblique angle therefrom preferably from one of its upper corners, said head and shank 40 being made of any suitable metal preferably aluminum. This head 1 has an opening 3 extending transversely therethrough to form a knife receiving seat and this opening is herein shown rectangular in configuration.

45 A set screw 4 extends through the head into the opening 3 and is designed to adjustably mount a knife blade 5 in said opening, said blade being herein shown pointed and beveled on one face to facilitate the cutting of 50 the channel in the shoe sole and it may be projected or retracted more or less if desired to vary the depth of the channel to be cut. A shoulder 6 extends laterally from one side of the head 1 at the front of the 55 opening 3 therein and has its lower face beveled or inclined upwardly and forwardly

to form a guide for the shoe sole which is cut during the channeling operation to form a lip L designed to be secured over the stitches after the sole has been fastened to the shoe. As shown in Fig. 2 the shoe sole passes under the lower end of the shoulder 6 and the leather lip L cut by the blade 5 passes over the upper beveled face of the knife during the cutting operation. An 60 apertured lug 7 depends from the head 1 at the side opposite that carrying the shoulder and has a set screw 8 adjustably mounted therein for regulating a gage 9 disposed between said lug and the shouldered side of 65 the head, and which is designed to regulate the width of the cut to be made, whereby a deeper or shallower cut may be formed as desired. This gage 9 as shown is disposed edgewise and is curved longitudinally 70 throughout its length with its concaved face disposed outwardly and which is adapted to engage the edge of the leather being channeled and thereby limit the inward movement of the knife point. This gage 9 is 75 carried by a spring arm 10 herein shown in the form of a resilient strip of metal secured at one end to the head 1 and bowed outwardly intermediately of its ends, the gage 9 being formed integral therewith and ex- 80 tending in a plane substantially at right angles to the bowed portion 11 thereof, said bowed portion affording a spring action for the gage, the resiliency thereof causing this gage to normally spring backward toward 85 the apertured lug 7 and against the rear face of which the set screw 8 is designed to engage for forcing the gage forward against the tension of the spring thereof.

In the use of this device the knife blade 5 90 is first adjusted in the seat 3 to project the cutting edge and point thereof the desired extent for forming a channel of the required depth and the set screw 4 is then screwed home to hold said blade in this position. When the blade has been so positioned and the gage 9 has been set to limit the inward movement or cutting extent of the blade 5 95 the tool is ready for use and is applied by engaging the knife with the leather to be cut with the beveled face of the guard leather 6 positioned on top of the shoulder so that the lip cut by the knife will be guided between said guard and the knife blade as is 100 shown clearly in Fig. 2.

110 From the above description the operation of the device will be thoroughly understood

and it will be seen that an inexperienced operator may use this tool to properly channel the leather for forming the shoe, the object of which is to cut a thin channel around the edges of the lower sides of the soles preparatory to the sewing of the sole on the shoe.

I claim as my invention:

- 10 1. A leather channeling tool comprising a head having an opening extending transversely therethrough to form a knife seat, a knife mounted upon said seat, a screw mounted in said head and intersecting said opening and adapted to clamp said knife in adjusted position, a gage mounted on said head and arranged below said knife, a lug depending from said head at one side thereof, and a screw adjustably mounted in said lug in position to engage and vary the position of said gage.
- 15 2. A leather channeling tool comprising a head having an opening extending transversely therethrough to form a knife seat, a knife mounted upon said seat, a screw mounted in said head and intersecting said opening and adapted to clamp said knife in adjusted position, a gage disposed below said

knife, said gage being curved longitudinally and having its concaved face disposed outwardly, a spring arm integrally secured to one end of said gage and extending in a plane at right angles thereto, said arm being secured at its free end to one side of said head and having its intermediate portion bowed outwardly, and means for adjusting said gage transversely of the head.

3. A leather channeling tool comprising a head having an opening extending transversely therethrough to form a knife seat, a knife mounted upon said seat, a screw mounted in said head and intersecting said opening and adapted to clamp said knife in adjusted position, and a guide lug extending laterally from one side of said head in advance of the knife opening therein, said lug having an upwardly curved lower face.

In testimony whereof I have hereunto set my hand in presence of two subscribing witnesses.

CHARLES M. THOMPSON.
